UNITED STATES PATENT OFFICE

113,643

DESIGN FOR A MANICURE DRIER

Frank Von, Los Angeles, Calif.

Application November 9, 1938, Serial No. 80,976

Term of patent 14 years

To all whom it may concern:

Be it known that I, Frank Von, a citizen of the United States, residing at Los Angeles, in the county of Los Angeles and State of California, have invented a new, original, and ornamental Design for a Manicure Drier, of which the following is a specification, reference being had to the accompanying drawing, forming a part thereof.

I claim:

The ornamental design for a manicure drier, substantially as shown.

FRANK VON.
